UNITED STATES PATENT OFFICE.

JACOB H. GENTER, OF NEWBURGH, NEW YORK.

AUTOMATIC ANNUNCIATOR.

1,101,429.

Specification of Letters Patent. Patented June 23, 1914.

Application filed May 14, 1913. Serial No. 767,564.

To all whom it may concern:

Be it known that I, JACOB H. GENTER, a citizen of the United States, and a resident of Newburgh, in the county of Orange and State of New York, have invented a new and Improved Automatic Annunciator, of which the following is a full, clear, and exact description.

The invention relates to projecting apparatus for projecting pictures or other subject matter on a screen, wall, sidewalk or other surface.

The object of the invention is to provide a new and improved automatic annunciator arranged to announce time and legends representing advertisement or titles to vaudeville acts, or titles for moving pictures and the like.

In order to accomplish the desired result use is made of a projecting apparatus, a slide in the field of the projecting apparatus and provided with a time dial, pointers in the field of the said projecting apparatus and arranged in indicating position relative to the said time dial to be projected with the time dial onto a distant surface to indicate the time of the day or night, and a timepiece for turning the said pointers in conformity with time.

A practical embodiment of the invention is represented in the accompanying drawings forming a part of this specification, in which similar characters of reference indicate corresponding parts in all the views.

Figure 1 is a sectional side elevation of the annunciator on the line 1—1 of Fig. 2; Fig. 2 is a sectional plan view of the same on the line 2—2 of Fig. 1; Fig. 3 is a cross section of the same on the line 3—3 of Fig. 4; Fig. 4 is an enlarged cross section of the same on the line 4—4 of Fig. 1 and showing more particularly the mechanism for turning the pointers around; Fig. 5 is a sectional side elevation of the same on the line 5—5 of Fig. 4; and Fig. 6 is an enlarged sectional side elevation of the actuating mechanism for the slide carrier.

In carrying out the invention use is made of a projecting apparatus A having a casing A' in which is mounted an objective or projecting lens B and a source of light D coacting in conjunction with a reflector D' for reflecting the rays of light parallel to the objective or projecting lens B. The casing A' is removably held on a bracket E attached to a wall, post or other suitable sup-

port and having a rod E' passing through an apertured boss A² held in the bottom of the casing A'. The boss A² is provided with a set screw E² adapted to engage the rod E' so as to securely fasten the casing A' on the rod E' of the bracket E. Within the casing A' of the projecting apparatus A is mounted to rotate intermittently a slide carrier F, preferably in the form of a skeleton wheel provided at its peripheral face with guideways F' for the reception of removable slides G containing the subject matter to be projected by the projecting apparatus onto a distant screen, wall, sidewalk or other surface. By reference to Figs. 1 and 2, it will be noticed that the source of light D and the reflector D' are arranged within the slide carrier F in such a manner that the slides G move successively into the field of the projecting apparatus, that is, between the reflector D' and the objective B.

The slide carrier F is rotated intermittently at the option of the operator in charge so as to permit of displaying the subject matter of the slide G, in active position at the time, any desired length of time, and for this purpose the following arrangement is made: The slide carrier F is provided with a hub F² mounted to rotate loosely on a shaft H attached to the door or cover A³ on one side of the casing A', and on the said hub F² is secured a gear wheel I (see Figs. 2 and 6) in mesh with a gear wheel I' secured on a transversely-extending shaft I² journaled in suitable bearings arranged on a bracket A⁴ attached to or forming part of the door A³. On the shaft I² is secured a toothed wheel J engaged by an escapement lever J' fulcrumed at J² on the bracket A⁴. The escapement lever J' is provided with an arm J³ extending between two pins K' held on an armature lever K fulcrumed loosely on the shaft I². The armature lever K is adapted to be swung downward by the action of a pair of electro-magnets L when the latter are energized, and a spring K² connected with the free end of the armature lever K serves to swing the armature lever K upward whenever the electro-magnets L are deenergized. The electro-magnets L are in an electric circuit L' provided with a battery or other source of electrical energy L² and with a switch L³ under the control of an operator at any desired distant point.

When the switch L³ is closed the electro-

magnets L are energized to swing the lever K downward, and when the switch is opened the electro-magnets L are deenergized to allow the spring K² to swing the armature lever K upward. On the armature lever K is fulcrumed a pawl K³ adapted to engage the teeth of the wheel J, and the said pawl K³ is pressed on by a spring K⁴ attached to the lever K to hold the pawl in engagement with the wheel J. Now when the armature lever K is swung downward the pawl K³ guides over the teeth of the wheel J and at the same time the armature lever K actuates the escapement lever J' by the pin 15 K' so as to release the wheel J, and when the lever K swings upward the pawl K³ turns the wheel J until the escapement lever J' again locks the wheel J against further rotation. It will be noticed that when the 20 wheel J is rotated in the direction of the arrow a' then a rotary motion is given by the gear wheels I and I' to the slide carrier F so that the next following slide G is moved into the field of the projecting apparatus. It is understood that the switch L³ is opened and closed as often as is necessary for turning the slide carrier F sufficiently far to move the next following slide G, or any other slide, into the field of the 25 projecting apparatus.

Each of the slides G is provided with a legend G' or with a picture or with any other desirable subject matter to be projected (see Fig. 3), and each slide G is also 30 provided with a time dial G² having a graduation and numerals indicating hours and minutes so that this dial is projected with the subject matter G' onto the distant surface.

An hour pointer N and a minute pointer N' extend into the field of the projecting apparatus A and are arranged in indicating position relative to the time dial G² to be projected with the time dial onto the distant surface to indicate time. The pointers N and N' are mounted on the forward ends of shanks or rods N², N³ extending lengthwise in the slide carrier F and being secured at their rear ends to gear wheels O, O' 45 mounted to turn on a circular bearing P having a bracket P' attached to the housing of a timepiece Q such as a clock or watch secured to the casing A' at the inside thereof, as plainly shown in Figs. 1, 4 and 5. The gear wheels O and O' are in mesh with gear wheels Q', Q² attached to the hour and minute arbors of the timepiece Q so that the gear wheels O and O', the shanks N², N³ and the pointers N, N' are turned in conformity with time, so that the pointers when projected onto a distant surface indicate the time of the day or night on the projected image of the dial G². By reference to Fig. 5 it will be seen that the shank N² is secured 55 to the front face of the gear wheel O while

the shank N³ extends through the bearing P and is secured to the rear face of the other gear wheel O'. The path of rotation of the shanks is outside of the reflector D' to permit turning of the shanks without interference of the reflector. 70

The reflector D' is mounted with its back on a post D² extending rearwardly and passing through the bearing P, the rear end being adjustably secured to a transverse rod D³ attached to the casing A'. A set screw D⁴ serves to fasten the post D² to the rod D³. The source of light D is mounted on a post D⁵ secured to the casing A', the said source of light being mounted outside of the path of rotation of the shanks N², N³, as will be readily understood by reference to Fig. 1. 80

It is understood that when the projecting apparatus is in use the slide carrier F is intermittently rotated at the option of the operator manipulating the switch L³, and as each slide G is provided with a time dial G² such time dial is projected onto a distant surface whenever the dial is in the path of the projecting apparatus. As the pointers N and N' are always in the field of the projecting apparatus and turn by the timepiece Q in conformity with time, it is evident that the images of the pointers projected on the distant surface indicate correct time on the image of the projected graduation. From the foregoing it will be seen that by the arrangement described any desired subject matter such as a title to a vaudeville act or the title of a moving picture can be projected onto the distant screen on which the moving picture appears, together with the correct time of the day or night. 90

Having thus described my invention, I claim as new and desire to secure by Letters Patent:

1. The combination in a projecting apparatus, of a source of light, a reflector, a projecting lens, a plurality of slides arranged to be brought successively between said reflector and said lens, each of said slides being provided with a time dial, a timepiece disposed in the rear of said reflector, a minute pointer and an hour pointer disposed between said reflector and said projecting lens in close proximity to the path of said slides and a shank for each of said pointers extending rearwardly and being operatively connected with said timepiece. 110

2. In combination, a projecting apparatus, a slide provided with a time dial and extending in the field of said projecting apparatus, an hour pointer, a minute pointer, said pointers extending in the field of the projecting apparatus and arranged in indicating position relative to said time dial, said pointers having rearwardly extending shanks, a time piece disposed in the rear of the field of the projecting apparatus, and 120

- hour and minute wheels driven by said time piece and being connected with the respective pointer shanks.
3. In combination, a projecting apparatus, 5 a slide provided with a time dial and extending in the field of the said projecting apparatus, an hour pointer, a minute pointer, the pointers extending in the field of the projecting apparatus and arranged 10 in indicating position relative to the said time dial, the pointers having shanks, a timepiece, and hour and minute wheels driven by the said timepiece and to which the shanks of the said pointers are attached.
- 15 4. In combination, a projecting apparatus, a slide carrier in the form of a wheel mounted to turn intermittently in the said projecting apparatus, slides mounted on the peripheral face of the said slide carrier and each provided with a time dial, the said 20 slides being adapted to move successively into the field of the projecting apparatus, means for intermittently rotating the said slide carrier, an hour pointer, a minute pointer, the said pointers extending into the 25 field of the projecting apparatus and arranged in indicating position relative to the said time dial, the said pointers having shanks, and a timepiece provided with driven hour and minute wheels on which the 30 said shanks are secured.

In testimony whereof I have signed my name to this specification in the presence of two subscribing witnesses.

JACOB H. GENTER.
